MOP CONSTRUCTION

Walter H. Pleiss, Ludington, Mich.

Application March 25, 1935, Serial No. 12,829

3 Claims. (Cl. 15—153)

This invention relates to improvements in a mop construction.

Some of the primary purposes of the present invention are to produce a mop which will be economical to manufacture, is made of few and easily stamped parts and is sturdy in construction so as to withstand the abuses to which a mop is subjected.

Another object of the invention is to provide 10 a construction whereby the mop head or the mop-cloth clamping head may be assembled as a unit. Also, the mop head may be positioned on the handle and held thereon by a single pin means. A further object of the invention is concerned with the particular construction in which 15 the clamping of the mop-cloth in the clamping head exerts that same force to hold the unit in assembled relation.

An understanding of the invention may be had 20 from the following description, taken in connection with the accompanying drawing, in which,

Fig. 1 is an elevation of the mop construction with the handle thereof broken off.

Fig. 2 is a vertical central sectional view 25 through Fig. 1.

Figs. 3 and 4 are horizontal sectional views taken along lines 3—3 and 4—4, respectively of Fig. 1.

Like reference numerals refer to like parts 30 throughout the several figures of the drawing.

The mop construction consists of a bail having a portion 1 at right angles to the handle of the mop, the outer ends of the portion 1 thence being bent at right angles forming the portion 2 35 extending parallel to the axis of the handle, the ends then bent angularly inward to form the portion 3, the bail terminating in the short portion 4 extending parallel to the handle.

An assembling bracket 5 is provided for mounting the bail to the handle and is formed from 40 two identical stampings each having a semi-cylindrical portion, which when assembled form the cylinder 6 into which the end of the handle of the mop extends. Flanges 7 extend from the diametrically opposite edges of the portions 6 45 and are welded or otherwise fastened together as indicated by numeral 7a and are formed with channel portions 8 parallel with the cylindrical portion 6 to contain the short straight ends 4 of the bail and the channel formed in the flange 7 then extends angularly outwardly at 9 to surround part of the angular portion 3 of the bail. A ferrule 10 is forced over the inner end of the 50 assembling bracket with a tight press fit and

is of substantially circular form having outwardly extending portions to fit over the channels 4 on both sides of the assembling bracket. The ferrule 10 has a central opening 10a at its outer end through which the handle 13 projects. An opening 11 is bored through the ferrule 10, the assembling bracket 5 and the handle 13 and a pin 12 is permanently positioned in this opening to secure the handle to the bracket.

The cylindrical portion 6 of the bracket 5 extends outwardly beyond the outer end of the flange 7 and a ferrule 14 is forced over this extending portion of the cylinder 6 with a tight press fit being held thereon by friction. The ferrule 14 is reduced in diameter at its outer end 10 and an opening 15 is formed in the closed end of the ferrule through which the clamp screw slides during the clamping of the mop-cloth between the clamping head 17 and the portion 1 of the bail, said clamping being accomplished by means 15 of the knurled nut 18, through which the clamp screw 16 passes, resting against the outer closed end of the ferrule 14. The clamp screw 16 is positioned in and also slides in an opening 19 formed in the end of the handle.

The clamping head is formed of two identical plates formed with channels along their outer and side edges which channels are of the proper size to slide over the outer and side portions 1 and 2 of the bail. Each of the plates 20 has a 20 vertical channel formed therein, which, when the plates are secured together, form a cylindrical opening into which the outer end of the clamp screw is positioned. The clamp screw and the channels 22 each have flattened portions 23 and 24, respectively, formed thereon, to prevent the screw from slipping endwise out of the cylindrical opening formed when the plates 20 are spot welded or otherwise fastened together as shown at 25.

From the foregoing description it will be seen that a mop construction has been conceived which, because of the few and simple stampings and the easily formed and assembled parts, is very economical to manufacture and sturdy in 30 construction.

The clamping of a mop cloth between the clamping head 20 and the part 1 of the bail by means of the knurled nut 18 exerts its pressure to hold the ferrule 14 in its frictionally engaged 35 relation to the cylindrical portion 6 of the assembling bracket 5.

The mop head is formed as a complete unit before being mounted on the handle and when mounted on the handle by means of the pin 12 50

the pull of the handle has no tendency to pull the unit apart.

Having thus described my invention, the particular construction which I claim as new is defined in the appended claims and is to be considered comprehensive of all forms of structure coming within their scope.

I claim:

1. In a mop construction, an elongated handle, 10 a bail formed with straight parallel ends and an angular portion adjoining each of the ends, means for mounting the elongated handle on the bail comprising, an assembling bracket formed of two similar parts, said similar parts being formed 15 with depressed portions which, when secured together, form a portion shaped to receive the handle, flanges extending from each of the opposite edges of the depressed portions of the parts of the assembling bracket, a channel formed in 20 the outer edge of each of the flanges to receive the straight and angular portions of the bail when secured together and means for securing the parts of the assembling bracket together.
2. In a mop construction, an elongated handle, 25 a bail formed with straight parallel ends and an angular portion adjoining each of the ends, means for mounting the elongated handle on the bail comprising, an assembling bracket formed of two similar parts, said similar parts being formed with

depressed portions which, when secured together form a portion shaped to receive the handle, flanges extending from each of the opposite edges of the depressed portions of the parts of the assembling bracket, a channel formed between the 5 outer edges of each adjacent pair of flanges to receive the straight and angular portions of the bail when secured together and means for securing the parts of the assembling bracket together.

3. A device of the character described having 10 an elongated handle therefor and also having a bail formed with straight parallel ends and an angular portion adjoining each of the straight portions, means for mounting the bail on the handle comprising, an assembling bracket formed 15 of opposed parts, each of said parts having opposed recesses which, when the parts are fastened together, form a recess shaped to receive the handle therein, said opposed parts each having channels formed therein which, when the parts 20 are fastened together form openings to receive the ends of the bail therein, a ferrule positioned over the ends of the bail and encircling the assembling bracket to hold the several parts in assembled relation and means extending through 25 the ferrule and elongated handle whereby the same are held together.

WALTER H. PLEISS.
